LOUIS COURTOT, OF PARIS, FRANCE, ASSIGNOR TO AMERICAN RADIATOR COMPANY, OF CHICAGO, ILLINOIS, A CORPORATION OF NEW JERSEY.

SHAKING MECHANISM FOR FURNACE-GRATES.

1,232,006.

Specification of Letters Patent.

Patented July 3, 1917.

Application filed April 15, 1914. Serial No. 831,980.

To all whom it may concern:

Be it known that I, LOUIS COURTOT, a citizen of the Republic of France, residing at Paris, in the Republic of France, have invented certain new and useful Improvements in Shaking Mechanism for Furnace-Grates, (for which I have obtained Letters Patent of the Republic of France, dated April 24th, 1913, No. 457,110,) of which the following is 10 a full, clear, and exact specification.

My invention relates to improvements in furnaces, and the same has for its object more particularly to provide a simple, efficient and reliable means for removing the 15 clinker, ashes and other material which may deposit upon or adhere to the surface of the grate.

Further said invention has for its object to provide means more particularly adapted 20 for use in connection with furnaces having water grates or other forms of grates whose bars are fixed and therefore incapable of being agitated or rocked in order to remove any clinker, ashes or other matter which may 25 collect upon or adhere to the grate bars.

Further said invention has for its object to provide a grate with a shaking mechanism comprising a member or series of members movably disposed intermediate the fixed bars 30 forming the grate, and means whereby said movable members may be actuated to raise the same above the upper surfaces of said grate bars in order to remove any clinker, ashes or other matter which may deposit 35 upon or adhere to the grate bars and thus interfere with the due passage there through of the air necessary to insure the proper combustion of the fuel.

Further said invention has for its object 40 to provide a shaking mechanism which may be readily applied to existing furnaces without necessitating any material change in the construction of the furnace or its grate.

To the attainment of the aforesaid objects 45 and ends, my invention consists in the novel details of construction and in the combination, connection and arrangement of parts hereinafter very fully described and then pointed out in the claims.

50 In the accompanying drawings forming part of this specification, wherein like numerals of reference indicate like parts,—

Figure 1 is a detail side view partly in section, showing a portion of a sectional

steam boiler and grate, provided with one 55 form of shaking mechanism, constructed according to and embodying my said invention: the said section being taken on the line 1—1 of Fig. 2;

Fig. 2 is a detail top view of the construction shown in side elevation at Fig. 1;

Fig. 3 is a detail side view partly in section showing a modified form of shaking mechanism;

Fig. 4 is a detail top view of the same; 65

Fig. 5 is a front elevation showing the lower portion of a boiler section and grate and a modified form of shaking mechanism applied thereto, and

Fig. 6 is a similar view showing a further 70 modification.

In the construction illustrated at Figs. 1 and 2, 10, 10 designate the opposite water legs of a boiler section having formed integrally therewith water grate bars 11, 11. 75 The said bars 11, 11 are each formed of two parts which extend inwardly toward each other from said opposite legs of the boiler section, and terminate at about the center of the interval between said legs. 80

The said grate bars 11, 11 are provided upon their opposing vertical, longitudinal sides with laterally-extending projections 12, 12 which register with each other, and at a point intermediate of their ends said bars 85 may be provided with several somewhat longer registering projections 13, 13 which serve to aid in maintaining the shaking members, hereinafter described, duly positioned between said bars, and guided in 90 the course of their movements.

Each pair of water grate bars is provided in the upper surfaces of their transversely separated ends with registering recesses 14, 14 to receive and support the trunnions 15, 95 15 of a pivoted shaking member or bar 16, which is substantially co-extensive in length with two bar sections which jointly constitute one grate bar. Each shaking member or bar is somewhat narrower than the space 100 provided between each pair of grate bars within which space said shaking member or bar is adapted to work, and is provided at one of its ends with a depending arm 17 which extends below the grate bar, and is 105 pivotally connected by means of a pin and slot with an arm 18 fixed upon a shaft 19 arranged below the grate at right angles to

the bars and is supported in bearings 20, secured to the boiler sections.

The forward end of the shaft 19 extends through the front of the boiler, and is designed to receive either a fixed or removable operating handle or lever 21, as shown in dotted lines.

In order to operate the shaking mechanism it merely becomes necessary to oscillate the operating handle or lever 21, whereby the shaft 19 will be rocked and cause the opposite ends of the shaking members or bars 16 to be rocked in unison and assume the positions indicated by broken lines at

Fig. 1. Any clinker, ash or other incombustible material which may have become deposited upon or adhere to said grate bars or the shaking members therebetween will thus be loosened, and caused to fall between said bars and into the ash pit below the grate.

In the construction illustrated in Figs. 3 and 4, 10', 10' designate the opposite water legs of a boiler section having integrally formed water grate bars 11', 11'. The said water grate bars 11', 11' are also each formed of two parts and terminate at about the center of the space intervening between the said legs. The said grate bars 11', 11' are provided upon their opposite sides with laterally extending projections 12', 12' which register with corresponding projections 12', 12' arranged upon the bars of the adjoining boiler sections 10', 10'. Midway between the free and secured ends of said grate bars 11', 11' are provided longer laterally extending projections 13', 13' which extend beyond the ends of the shorter projections 12', 12' which serve to maintain the intermediate shaking members duly positioned therebetween and to guide the same in the course of their movements.

The water grate bars 11', 11' are provided upon their adjoining faces at about the point or junction of said water grate bars 11', 11' with the legs 10', 10' of the boiler section with recesses 14', 14' which are rounded at their bases to form sockets.

Between the adjoining grate bars 11', 11' are arranged shaking members, consisting of flat bars 16', 16' provided at their outer ends with oppositely-arranged bearings 15', 15' supported in the sockets 14', 14' provided in the sides of said grate bars. The shaking members each comprise a horizontal portion and a vertical depending portion 17' which extends downward between the adjoining grate bars and projects below the lower surface thereof.

19', 19' denote shafts which are suitably supported, in bearings 20', 20' provided upon certain of the boiler sections. The forward end of one of the shafts 19', 19' may project outwardly through the front of the boiler body and has an operating lever or

handle 21', thereon connected by a link 22' with a short arm 22* on the other of said shafts.

Upon each shaft 19', 19' are provided a series of depending arms 18', 18' having enlarged lower ends 18*, 18* which are adapted to contact with the outer sides of the depending vertical portions 17', 17' of the shaking members. The arms 18', 18' correspond in number with the number of shaking members arranged intermediate the grate bars 11', 11' so that there shall be one arm 18' for each depending portion 17' of said grate bars.

In order to remove any clinker, ash or other incombustible matter which may deposit upon or adhere to the grate bars 11', 11' or to the horizontal members 16', of the shaking members, it merely becomes necessary to oscillate the operating lever 21', which will cause the depending arms 18', 18' in engagement with the depending members 17', 17' of the shaking members, to raise the free ends of the horizontal members thereof above the plane of said grate bars, as shown in the dotted lines at Fig. 3, and thus cause any matter which may be deposited upon or adhere to the grate bars or to said horizontal members 16', 16' to be loosened and drop between said bars into the ashpit below the grate.

It will be observed that the horizontal members 16' of the shaking members are relatively thin and fit freely between the adjoining grate bars 11', 11' and that the said horizontal portions of said shaking members 16', 16' are guided in the course of their oscillations by the longer lateral projections 13', 13' extending from the opposite sides of the grate bars 11', 11'.

In the construction illustrated at Fig. 5, the boiler section comprising the legs 10^a, 10^a and the grate bars 11^a, 11^a are of the same construction as described in connection with the main figure heretofore described. In this construction however the shaking members comprising the horizontal arms 16^a, 16^a are also pivotally supported at their outer ends in sockets 14^a, 14^a provided upon the grate bars at about the junction thereof with the legs 10^a, 10^a of the boiler sections. Each of said bars 16^a, 16^a is provided with a depending member 17^a, which has an outwardly projecting toe 17*.

19^a, 19^a denote shafts which are suitably supported below the grate and provided with a series of depending arms 18^a, 18^a each of which has a perforation therein, engaging with the stud 17', on one of the toes 17*. The forward end of one of the shafts 19^a, is provided with an operating lever 21^a, and the other of said shafts 19^a, is provided at its corresponding end with a short arm 21*, which is pivotally connected with the operating lever 21^a by a link 22.

In this construction when the lever 19^a is oscillated the free ends of the horizontal shaking members 16^a, 16^a will be caused to rise alternately above the plane of the upper surfaces of the grate bars 11^a, 11^a and thus tend to break up and loosen any matter which may be deposited upon or adhere to the said grate bars 11^a, 11^a or upon the intervening horizontal members 16^a, 16^a of the shaking mechanism, and thus cause said matter to drop through said bars and into the ashpit.

In the construction illustrated at Fig. 6 the legs 10^b, 10^b of the boiler section are provided with grate bars 11^b, 11^b. The shaking mechanism in this construction is composed of a plurality of bell crank levers 16^b, 16^b which are pivotally secured at the junction of their horizontal and vertical portions to the opposite legs of said boiler sections at the junction of the grate bars with said legs of boiler sections.

In this construction, however, the horizontal members of said bell crank levers 16^a, 16^a are equal in length to the two grate bar sections which jointly constitute one grate bar, and therefore extend entirely across the grate. In this modification the said horizontal members are arranged in overlapping relation; that is to say, between each pair of grate bars 11^b, 11^b each of which is composed of two sections there are arranged two bell crank levers 16^a, 16^a.

It is to be noted that while my invention is designed more particularly for use in connection with water grates, which must of necessity be formed integrally with the boiler sections or be rigidly secured thereto, that the same may nevertheless be employed with equal advantage in combination with other types of rigid grate bars.

Having thus described my invention, what I claim and desire to secure by Letters Patent is:—

1. The combination of a grate having a plurality of separated bars with a shaking mechanism comprising a series of bell-crank members pivotally supported between said grate bars, a shaft operatively connected with the vertical portions of said bell-crank members, and means for actuating said shaft whereby to project the ends of the horizontal portions of said bell-crank members upwardly above the horizontal plane of said grate, substantially as specified.

2. The combination of a grate having a plurality of separated bars with a shaking mechanism comprising a series of bell-crank members pivotally supported between said grate bars, a shaft supported at right angles to said bell-crank members and operatively connected with the vertical portions of said bell-crank members, and means for actuating said shaft whereby to project the ends of the horizontal portions of said bell-crank

members upwardly above the horizontal plane of said grate, substantially as specified.

3. The combination of a grate having a plurality of separated bars with a shaking mechanism comprising a series of bell-crank members pivotally supported intermediate said grate bars, a shaft supported at right angles to said bell-crank members, means for connecting said shaft with the vertical portions of said bell-crank members, and means for actuating said shaft whereby to project the ends of the horizontal portions of said bell-crank members upwardly above the horizontal plane of said grate, substantially as specified.

4. The combination of a grate having a plurality of separated bars with a shaking mechanism comprising a series of bell-crank members pivotally supported between said grate bars, a shaft supported at right angles to said bell-crank members, means connecting said shaft with the vertical portions of said bell-crank members, means for actuating said shaft whereby to project the ends of the horizontal portions of said bell-crank members upwardly above the horizontal plane of said grate, and means for guiding the free ends of the horizontal portions of said bell-crank members in their movement between said grate bars, substantially as specified.

5. The combination of a grate having a plurality of separated bars with a shaking mechanism comprising a series of bell-crank members arranged intermediate each pair of adjacent grate bars and pivotally supported at the center of their horizontal portions, a shaft supported at right angles to said bell-crank members, a series of arms depending from said shaft registering in number with said bell-crank members and pivotally connected to the vertical portions thereof, and an operating lever secured to said shaft, whereby to actuate the same to cause the ends of the horizontal portions of said bell-crank members to be projected upwardly simultaneously between said grate bars and above the upper surface thereof, substantially as specified.

6. The combination with a grate having a plurality of separated bars, each composed of two sections separated from each other at about the center of the grate and provided with recesses, of a shaking mechanism comprising a series of bell-crank members arranged intermediate each pair of adjacent grate bars, trunnions provided upon said bell-crank members and disposed within the recesses in said grate bars, a shaft supported below said grate at right angles to said bell-crank members, a series of arms depending from said shaft registering in number with said bell-crank members and pivotally connected to the ends of the ver-

tical, depending portions of said bell-crank members, and an operating lever secured to said shaft whereby to actuate the same to cause the ends of the horizontal portions of said bell-crank members to be projected upward simultaneously above the upper surface of said grate, substantially as specified.

Copies of this patent may be obtained for five cents each, by addressing the "Commissioner of Patents, Washington, D. C."

Signed at the city of Paris, Republic of France, this 17th of March one thousand nine hundred and fourteen.

LOUIS COURTOT.
